INVENTOR.

Wellington Ovens.
BY ATTORNEY.

UNITED STATES PATENT OFFICE.

WELLINGTON OVENS, OF SILVERTON, COLORADO.

ATTACHMENT FOR SPIRIT-LEVELS.

SPECIFICATION forming part of Letters Patent No. 711,880, dated October 21, 1902.

Application filed May 23, 1902. Serial No. 108,721. (No model.)

To all whom it may concern:

Be it known that I, WELLINGTON OVENS, a citizen of the United States of America, residing at Silverton, in the county of San Juan and 5 State of Colorado, have invented certain new and useful Improvements in Attachments for Spirit-Levels; and I do declare the following to be a full, clear, and exact description of the invention, such as will enable others skilled in 10 the art to which it appertains to make and use the same, reference being had to the accompanying drawings, and to the figures of reference marked thereon, which form a part of this specification.

15 My invention relates to an improved attachment for spirit-levels; and it consists of a device attached to one end of the level-bar and adapted to be adjusted to measure the inclination of a surface as compared with the 20 horizontal or vertical.

25 My object is to provide a device of this class which shall be simple in construction, economical in cost, reliable, durable, and efficient in use; and to these ends the invention 25 consists of the features hereinafter described and claimed, all of which will be fully understood by reference to the accompanying drawings, in which is illustrated an embodiment thereof.

30 In the drawings, Figure 1 is a perspective view of a spirit-level provided with my improved attachment. Fig. 2 is a section taken on the line 2 2, Fig. 3. Fig. 3 is an end elevation of a spirit-level provided with my 35 improvements.

The same reference characters indicate the same parts in all the views.

Let the numeral 5 designate the bar of the ordinary spirit-level, to one end of which, as 40 shown in the drawings, is attached a plate 6 by means of screws 7. To this plate a bracket 9 is made fast by means of a thumb-screw 8. The bracket is also provided with a lug 10^a, which enters a socket formed in the plate 6. 45 In the sides of this bracket are formed ways in which a plate 10 is slidable. The central portion of the plate is cut out to make room for the thumb-screw 8 and to permit the plate to slide vertically or at right angles to the 50 length of the bar 5. The top of the plate 10 projects outwardly, as shown at 10^a, and this projection is provided with a threaded open-

ing to receive an adjusting-screw 12, which is journaled in the outwardly-projecting top part 9^a of the bracket. This screw is provided with a milled head 12^a, which forms a shoulder engaging the bracket above, while a collar 13 is made fast to the screw immediately below the bracket part 9^a, whereby the screw is prevented from traveling in either 60 direction.

From the construction and arrangement described it is evident that as the screw 12^a is turned the plate 10 may be moved up and down at will. The lower part 10^c of the 65 plate is graduated to enable the user to determine the exact degree of the inclination of any surface considered with reference to either a vertical or horizontal plane.

It is evident that the details of construction 70 as herein described may be varied at pleasure. If the bar 5 is made of metal, the plate 6 may be dispensed with and the bracket-plate 9 secured directly to the end of the bar. As shown in the drawings, the top of the head 12^a of the 75 adjusting-screw is in the same plane with the upper edge or top of the plate 6. For small or narrow levels the plate 6 may be made shorter, while the other parts may be made of uniform size. In this event the head 12^a 80 of the screw will project above the top or upper longitudinal edge of the level.

When in use, the level is placed upon the surface, and if the bubble of the glass tube 14 for horizontal surfaces or of the tube 15 85 for vertical surfaces indicates an inclination the screw 12 is turned to project the plate 10 below or beyond the edge 5^a of the instrument, which edge for the purposes of this specification will be termed the "lower" edge, 90 while the opposite edge is for convenience termed the "upper" edge. The graduated part 10^c of the slidable plate should be projected until the bubble indicates that the bar 5 is either horizontal or vertical, as desired. 95 The degree of the projection will be indicated by the graduation of the plate.

Having thus described my invention, what I claim is—

1. The combination with a level of the class 100 described, of a bracket attached to one end of the level-bar and having outwardly-projecting sides in which are formed ways open at the bottom, a set-screw for fastening the

bracket to the bar, a plate slideable in the ways of the bracket, said plate being cut out in the center to make room for the set-screw, the plate being provided with a projection at 5 the top extending at right angles to the body of the plate and provided with a threaded opening, the bracket having a top projection located above the projection of the plate, and an adjusting-screw journaled in the bracket 10 projection and threaded in the projection of the slideable plate, substantially as described.

2. The combination with a level of the class described, of a plate attached to one end thereof, a bracket provided with a lug adapted to enter an opening in the stationary plate, the bracket also having a threaded opening registering with the threaded opening in the plate, the bracket having a projection extending outwardly from its top and being 15

provided with side projections in which are 20 formed ways open at the bottom, a plate slideable in the ways of the bracket and having a right-angular projection at its top, said projection being provided with a threaded opening, the central portion of the slideable 25 plate being cut away, an adjusting-screw journaled in the bracket projection and threaded in the projection of the slideable plate, and a set-screw engaging the threaded openings of the bracket and stationary plate 30 to hold the bracket in place, substantially as described.

In testimony whereof I affix my signature in presence of two witnesses.

WELLINGTON OVENS.
